UNITED STATES PATENT OFFICE.

FLORENCE HEIN BISCHOFF, OF NEW YORK, N. Y.

PARING APPARATUS.

1,189,782.

Specification of Letters Patent.

Patented July 4, 1916.

Application filed September 8, 1914. Serial No. 860,637.

To all whom it may concern:

Be it known that I, FLORENCE HEIN Bischoff, a citizen of the United States, and a resident of New York, county and State 5 of New York, have invented a certain new and useful Improvement in Paring Apparatus, of which the following is a full, clear, and exact specification.

This invention relates to a class of household articles.

My invention has for its object primarily to provide a paring apparatus designed to be employed for accomplishing with facility the work of removing the rind as well 15 as slicing in ribbon-like strips certain classes of fruits and vegetables, in order to overcome the objections attendant to the use of a sharp instrument such as a knife when manipulated in the usual way by 20 hand. This is attained mainly by providing a frame having adjustably mounted thereon a rotatable carrier element to which the article to be pared is removably applied for being revolved in the path of 25 movement of a yieldingly held adjustable cutting blade which is caused to be guided in the radius of a circle to suitable positions of contact with the article.

Other objects of the invention are to provide means for rotating the carrier element; 30 to provide a yielding stop to permit the carrier element to be adjusted in the frame whereby articles of various sizes may be suitably positioned relatively to the center 35 of the radial positions of the cutting blade; to provide the cutting blade with a spring controlled presser element, or bar whereby the blade may be yieldingly forced into contact with the article being pared; to provide the presser element with a bracket 40 member pivoted to the frame so that the presser element and the blade may be swung to various circumferential positions; and to provide means to allow the swinging 45 bracket member to be manually adjusted as required during the operation of the apparatus.

A further object of the invention is to provide a paring apparatus of simple and 50 efficient construction, and which is susceptible of being made in different sizes so as to combine great durability.

With these and other objects in view, the 55 invention will be hereinafter more particularly described with reference to the accompanying drawings forming a part of this

specification in which similar characters of reference indicate corresponding parts in all the views, and will then be pointed out in the claims at the end of the description. 60

In the drawings, Figure 1 is a side elevation of one form of paring apparatus embodying my invention. Fig. 2 is a top plan of the apparatus. Fig. 3 is a fragmentary sectional view, partly in detail, taken on 65 the line III—III of Fig. 2. Fig. 4 is an enlarged elevation of the cutting blade and its supporting bracket used in the apparatus, and Fig. 5 is a section, partly in detail, taken on the line V—V of Fig. 4. 70

The paring apparatus has a frame 10 supported upon a base, as 11, which may be mounted on any suitable support, as 12, and this support may be held by means of a clamp 13, or otherwise. The frame 10 75 is formed in substantially an L-shape with a vertically disposed post 14, and a bar 15 extending from the lower end of the post. On the upper end of the post 14 is an apertured cross-head or bearing 16, the passage 17 80 therethrough being longitudinally disposed similarly to the bar 15. On top of the head 16 at one of its ends is a boss 18 in which is a threaded recess, and in proximity to the other end of the head is a second boss 19 having a vertically disposed passage 19^a 85 leading therethrough and also leading through the head to communicate with its passage 17.

In order to permit an article, such as an 90 apple, or other fruit, or vegetable, as 20, to be removably mounted on the apparatus so as to be pared, or sliced into ribbon-like strips, a revoluble carrier element, as 21, is provided. The carrier element 21 has a 95 rod or shaft 22 which is revolvably disposed through the longitudinal passage 17 of the cross-head 16, and this shaft is of a length so that its ends extend some distance beyond the ends of the cross-head. On one end of the shaft 22 is a fork, as 23, extending in spaced relation longitudinally above the bar 15 of the frame 10. On the other end of the shaft 22 is a crank handle 24 by which the shaft, the fork 23, and the article 20 is 100 manually revolved, though in instances this crank handle may be dispensed with, and instead thereof other suitable power propelling means may be employed for driving the carrier element. 105

At spaced intervals in the central part of the shaft 22 are a number of grooves 25, 25^a,

25^b, each of which is adapted to be registered with the passage in the boss 19 of the cross-head of the frame of the apparatus, and to permit the carrier element 21 to be 5 adjusted in the cross-head whereby articles of various sizes may be properly positioned for being pared, or sliced, a yielding stop, as 26, is provided. The stop 26 has a spring 27 preferably in the form of a strip of metal 10 having one of its ends secured to the boss 18 of the cross-head 16 by a screw passed through an opening in the spring and into the threaded recess of this boss. The spring 27 is of a length so that its other end is 15 disposed over the top of the second boss 19 of the cross-head 16, and in the passage of the second boss 19 is movably disposed a pin 28. The upper end of the pin 28 is in normal contact with the spring 27 so that 20 the tension of the spring will serve to force the pin inwardly of the cross-head 16. The lower end of the pin is rounded and seated in one of the grooves 25, 25^a, 25^b of the shaft 22 of the carrier element. The carrier element 21 is adapted to be adjusted in the 25 cross-head so that the axial center of the article being pared will be preferably on a vertical line with respect to the free end of the longitudinal bar 15 of the L-shaped 30 frame of the apparatus. To accomplish this adjustment the shaft 22 of the carrier element is moved accordingly backwardly or forwardly in the cross-head 16 of the frame for allowing the spring actuated pin 28 to 35 engage the proper one of the grooves 25, 25^a, 25^b of this shaft, the rounded lower end of the pin 28 permitting the shaft when moved by the exertion of slight force to be disengaged from its groove for being yieldingly seated in one of the other grooves 40 when the shaft is properly adjusted, and the carrier element will then be yieldingly held against accidental movement. In this manner articles of various sizes may be impaled on the forks 23 of the carrier element and suitably positioned for being pared, or sliced, as will be hereinafter more 45 fully explained.

For the purpose of conveniently paring or 50 slicing an article, such as fruit or vegetables of certain classes, I provide a form of cutting blade, as 29, which is caused to be guided in the radius of a circle to suitable circumferential positions of contact 55 with the article, and this blade is adjustably mounted on a spring controlled presser element, or bar, as 30. The blade 29 is rigidly held between the arms of a substantially U-shaped bracket 31, and this blade 60 is disposed on an incline, as shown, so that its cutting edge is spaced from the bottom of the bracket to provide a passage, as 32, between the blade and the bracket. The bracket 31 is pivoted, at 33, by means of a 65 downwardly extending pin which is freely

movable in a sleeve provided on one end of the presser element, or bar 30 so that the bracket and the cutting blade will be revolubly movable. The presser bar 30 is preferably curved slightly, and the opposite 70 end of the bar is pivoted by a pin 34 rotatably disposed through a sleeve 35 provided on the upper end of the vertical arm 36 of an L-shaped bracket member 37. The longitudinal arm 38 of the bracket member 75 37 is disposed toward the free end of the bar 15 of the frame of the apparatus. To the sleeve 35 of the arm 36 of the bracket is held one end of a spiral spring 39 which encircles the sleeve. The other end portion 80 of the spring 39 extends under the presser bar 30, and this end of the spring is held to the presser bar by a pin 39^a in proximity to the cutting blade 29. The tension of the spring normally serves to yieldingly force 85 the presser bar and the cutting blade toward the fork 23 of the carrier element 21.

Serving as means to manually guide the bracket member 37 and the presser bar 30 whereby the cutting blade will be moved 90 circumferentially to suitable positions in contact with the article being pared, or sliced, on the end of the arm 38 of the bracket 37 opposite to its vertical arm is formed the central part of a handle, as 40. 95 One end of the handle 40 is pivoted, at 41, by means of a bolt and thumb nut to the free end of the bar 15 of the frame 10, and the other end of this handle extends some distance outwardly at an angle from the frame 100 and from the bracket member 37.

When the apparatus is operated to pare, for example an apple, or a potato the article is removably impaled on the fork 23 of the carrier element 21, as illustrated, at 20, Fig. 105 2 of the drawings, and the carrier element is adjusted in the head, or bearing 16 of the frame, as above explained, so that the axial center of the article will be approximately on a vertical line with the end of the bar 15 110 which is pivoted to the handle 40. The shaft 22 of the carrier element is then driven by turning the crank handle 24, and in turn the article will be revolved accordingly after the cutting blade 29 has been suitably positioned in contact with the article. Through the medium of the presser bar 30 and the tension of its spring 39 the cutting blade will be yieldingly retained in contact with the article which will be pared, or sliced in 115 ribbon-like strips to a desired depth by suitably tensioning this spring. In order to cut various parts of the article the handle 40 is manually swung on its pivot longitudinally in backward or forward directions. 120 The bracket member 37, the presser bar 30, and the cutting blade will thereby be directed in the radius of a circle for quickly paring, or slicing the article circumferentially. Obviously the tension of the spring 130

39 of the presser bar 30 not only serves to guide this bar whereby the cutting blade will be held in contact with the article, but also tends to yieldingly force the presser bar 5 so that the movement of the blade will conform to irregularities in the surface of the article when these parts are properly directed by the manipulation of the handle 40.

In the foregoing description, I have embodied the preferred form of my invention, 10 but I do not wish to be understood as limiting myself thereto, as I am aware that modifications may be made therein without departing from the principle, or sacrificing 15 any of the advantages of this invention, therefore I reserve to myself the right to make such changes as fairly fall within the scope of the appended claims.

Having thus described my invention, I 20 claim as new and desire to secure by Letters Patent:—

1. In a paring apparatus, the combination with a frame including manually adjustable means for guiding in the radius of 25 a circle a blade yieldingly mounted on the adjustable means, of a rod with means to hold an article to be pared, said rod being manually rotatable in the frame as well as being adjustable in directions to and from 30 the path of movement of the blade, and a catch on the frame for engaging the rod to releasably hold the rod when in adjusted positions.

2. In a paring apparatus, the combination with a frame including manually adjustable means for guiding in the radius of a circle a blade yieldingly mounted on the adjustable means, of a rod with means to hold an article to be pared, and having 40 spaced annular grooves in its periphery, the said rod being manually rotatable in the frame as well as being adjustable in directions to and from the path of movement of the blade, and a spring actuated catch on 45 the frame for engaging the grooves of the rod to releasably hold the rod when in adjusted positions.

3. In a paring apparatus, in combination, 50 a frame with a bracket manually movable in the radius of a circle, a spring actuated

arm pivoted to the bracket, and carrying a cutting-blade, a rod with means to hold an article to be pared, said rod being manually rotatable in the frame as well as being adjustable in directions to and from the path 55 of movement of the blade, and a catch on the frame for engaging the rod to releasably hold the rod when in adjusted positions.

4. In a paring apparatus, in combination, a frame with a bracket manually movable 60 in the radius of a circle, a spring actuated arm pivoted to the bracket, and carrying a cutting blade, a rod with means to hold an article to be pared, and having spaced annular grooves in its periphery, the said rod 65 being manually rotatable in the frame as well as being adjustable in directions to and from the path of movement of the blade, and spring actuated means on the frame for engaging the rod to releasably hold the rod 70 when in adjusted positions.

5. In a paring apparatus, the combination with a frame including a blade manually movable in the radius of a circle, of a sleeve on the frame, a rod with means to 75 hold an article to be pared, said rod being manually rotatable in the sleeve as well as being adjustable in directions to and from the path of movement of the blade, and a catch on the frame for engaging the rod to 80 releasably hold the rod when in adjusted positions.

6. In a paring apparatus, the combination with a frame including a blade manually movable in the radius of a circle, of a 85 sleeve on the frame, a rod with means to hold an article to be pared, and having spaced annular grooves in its periphery, the said rod being manually rotatable in the 90 sleeve as well as being adjustable in directions to and from the path of movement of the blade, and spring actuated means on the frame for engaging the rod to releasably hold the rod when in adjusted positions.

This specification signed and witnessed 95 this fifth day of September, A. D. 1914.
